UNITED STATES PATENT OFFICE.

ABRAHAM NOBLE, OF SAN DIEGO, CALIFORNIA.

CAN OPENER.

Application filed August 2, 1923. Serial No. 655,271.

My invention relates to improvements in can openers, for opening tin cans; and some of the objects of my improvement are, first, to cut the top from a can easily, so that women and children, who have little physical strength, can open cans with little effort; second, to open a can more quickly than heretofore; third, to avoid the necessity of pushing the opener, to feed around the can; fourth, to render it unnecessary to hold or touch the can while it is being opened, and thus to avoid the possibility of injuring the hand; fifth, to cut the top of the can entirely off, clean, so as to leave no inwardly extending flange or burr, and thus to provide for the free exit of the contents; sixth, to open round, square, oblong or other shaped cans; seventh, to make it unnecessary to first punch a hole in the can in order to start the opener, or to drive or hammer a cutter into the can; eighth, durability; ninth, simplicity; tenth, comparative inexpensiveness of manufacture.

These and other objects I attain by means of the mechanism illustrated in the accompanying drawing, in which—

Fig. 1 is a side elevation; Fig. 2, a sectional view, on a horizontal plane, on line 1—1 of Fig. 1; and Fig. 3 is an enlarged detail top plan view of the cutter.

Similar reference characters refer to similar parts throughout the several views of the drawings.

In the preferable embodiment of my invention, shown in the drawing, a channel shaped frame, 1, is provided, which is provided with a suitable handle, 2, for holding the opener. The flanges, 3 and 4, of the channel shaped frame are formed with bearing holes at 5, 6, 7 and 8, to receive vertical shafts, 9 and 10, which are journaled therein. Shaft 9 is extended upward beyond frame 1 and provided at its upper end with a handle, 11, for rotating or turning the shaft, and with a driving gear, 12, which meshes with a driven gear, 13, mounted on the upper end of shaft 10. It is obvious that handle 11 may be mounted on shaft 10 instead of shaft 9.

A toothed feed and resistance disk or wheel, 14, is mounted on the lower end of shaft 9, so that it is rotated by means of handle 11. Wheel 14 is placed on the top of a can, 15, and engages the inner surface of rim 16 of the can, so that the teeth dig into the surface of the rim and the wheel feeds the opener positively around the can. It is obvious that

it may be rolled in either direction, so that the opener may be operated either right-handed or left-handed.

A cutter wheel, 17, is mounted on the lower end of shaft 10, so as to be rotated thereby, and is formed with a chisel shaped edge which is notched, so that the edge consists of a series of spaced cold chisels. The upper surface of wheel 17 is in a plane lower than the under surface of wheel 14 by the thickness of the tin of the can top, and the edge of wheel 14 overlaps the edge of wheel 17, so that cutter 17 pierces the wall of the can just under the top. It will be understood that the chisel toothed cutter 17 cooperates with wheel 14 in feeding positively around the can without effort to push or pull on the part of the operator, and he does not have to hold or turn the can or touch it with his hand. When the cycle is completed the can top is entirely severed from the wall and may be lifted off freely by the opener.

The bearing hole 8 is elongated, so that shaft 10 and cutter 17 is permitted to swing backward from wheel 14, as shown by dotted lines. By this means the opener may be freely applied over rim 16 of can 15.

A closing lever, 18, is pivoted on a stud, 19, secured in frame 1. Lever 18 is formed concave at the forward end to form a journal bearing for shaft 10, and serves to push the shaft forward at its lower end, and cutter 17 through the vertical wall of can 15 just under the lid and hold the cutter in cutting relation while the opener is being operated by means of handle 11. Lever 18 is shown in open relation by dotted lines.

As cutters 17 severs the tin as shown and described, the adjacent portion of the can wall, at 20, is sprung inward and springs back into normal position after the cutter has passed, so that an inward-extending flange or burr is not left whereby the free exit of the contents of the can might be interfered with, so that solid contents, as sliced pineapple, corned beef and the like, may be emptied bodily, and even semiliquid and liquid contents may be easily poured out without difficulty or waste. No sharp edge or burr, which might injure the hands, is raised in the can or the top. The cutter of my opener does not extend into the can so as to disturb the contents.

Furthermore, delicate hands are frequently injured in the act of punching a hole in the

tin in order to start the conventional can openers. This difficulty is entirely avoided by my improvement, the lever 18 being easily closed and the first incision of cutter 17 being 5 made without shock or uncertainty of hitting the mark. The well rounded handle 11 also is comparatively long, to provide ample leverage for the frailest person to operate the cutter even through the vertical seam of the 10 can.

The usual violent thumping, hammering and wrenching incident to opening cans is avoided and peace and quiet is promoted.

Having thus described my invention in its 15 present preferable embodiment, so that any one skilled in the art pertaining thereto may understand its construction, and any one may understand its use, I do not wish to be confined to the particular construction shown and 20 described, but contemplate varying the construction within the purview of the appended claims.

I claim—

1. In can opener, a frame having manual 25 holding means for one of the hands, manual torsional rotating means mounted on said frame for rotating cutting means with the other hand while the first named hand is manipulating said holding means, puncturing gear and self feeding toothed cutting means rotated and driven by said rotating means, and closing means for actuating and 30 retaining said cutting means in closed relation.

tion pivotally mounted on said frame in close proximity to said holding means.

2. In a can opener, a frame having manual holding means, a shaft journalled in said frame, resisting and auxiliary feeding means mounted on one end of said shaft, manual rotating means provided on the opposite end of said shaft, a second shaft journalled in said frame and driven through gearing by said manual rotating means, a cutter mounted on said second shaft, and a lever for actuating said cutter through the wall of the can so 40 fulcrumed on said frame that its power member is in close proximity to said manual holding means.

3. In a can opener, a frame having manual holding means, resisting and auxiliary feeding means rotatively mounted on said frame, a shaft journalled in said frame, circular cutting means mounted on said shaft, driving means for said resisting and auxiliary feeding means rotatively mounted on said frame, and a closing and locking lever for actuating said cutting means through the wall of a can and holding it in operative relation mounted in close proximity to said manual holding means so that it is manipulated by the same hand that holds said holding means, its work member being provided with a journal bearing in its free end and when fully closed stops on dead center and locks said shaft in closed relation.

ABRAHAM NOBLE.
